UNITED STATES PATENT OFFICE.

AUGUST KOPINSKI, OF CHICAGO, ILLINOIS.

AIR-BRUSH.

1,218,279.

Specification of Letters Patent. Patented Mar. 6, 1917.

Application filed May 29, 1915. Serial No. 31,285.

To all whom it may concern:

Be it known that I, AUGUST KOPINSKI, a citizen of the United States, and a resident of the city of Chicago, county of Cook, and 5 State of Illinois, have invented certain new and useful Improvements in Air-Brushes, of which the following is a specification.

My invention relates to improvements in air brushes and has for its object the production of a device of this character which will be of improved construction and efficient in operation.

Other objects will appear hereinafter.

The invention consists in the combinations and arrangements of parts hereinafter described and claimed.

The invention will be best understood by reference to the accompanying drawing, forming a part of this specification, and in 20 which—

Figure 1 is a vertical section of an air brush embodying the invention,

Figs. 2 and 3 are enlarged sections taken on lines $x-x$ and $y-y$ respectively of Fig. 25 1, and

Fig. 4 is a section taken on line $z-z$ of Fig. 1.

The preferred form of construction as illustrated in the drawing comprises an elongated cylindrical member 1 through which is formed an axial air passage 2. Rigidly secured to one end of the member 1 is a tubular member 3. Also mounted upon the member 1 is a connecting member 4 which is 30 clamped in position between the member 3 and a lock nut 5 threaded upon the member 1.

Threaded in the lower end of member 4 is the upper end of a downwardly extending 40 pipe 6, the upper end of the passage through said pipe communicating with a transversely extending passage 7 formed in the member 1 which is in open communication with the passage 2. The lower end of pipe 45 6 is inclosed in an ink, paint or pigment supply reservoir 8 having a screw cap 9 which is securely held in position against the lower end of member 4 by means of a collar 10 formed upon the pipe 6.

50 The forward end of passage 2 communi-

cates with a pigment nozzle 11 which is 55 threaded in the front end of member 1. Surrounding the nozzle 11 is an air nozzle 12 which is threaded upon the front end of member 1 as shown. The discharge through nozzles 11 and 12 is controlled by a needle 60 valve 13 secured at its rearward end in a member 14 which is threaded in the rearward end of member 1. The member 14 is provided with an exteriorly positioned knurled head 15 whereby the same may be 65 rotated in order to adjust the position of valve 13. The upper side of the member 1 is flattened or cut away in order to form a longitudinally extending air passage 16 which communicates at its front end with 70 the nozzle 12. The rearward end of passage 16 is connected by means of a circumferential passage or groove 17 formed in the rearward end of member 1, with a vertically extending passage 18 formed in a member 19 75 secured rigidly at its upper end to the rearward end of member 3. The lower end of passage 18 is connected with a compressed air supply tube 20 by means of a coupling member 21 threaded in the lower end of 80 member 19.

Secured to and projecting outwardly from the member 19 at right angles thereto is a handle piece 22 provided at its outer end with a grip 23 adapted to be engaged by the 85 hand when the device is in use.

The front of the handle piece 22 traverses the passage 18 and in order to preserve the continuity of said passage, is formed with a registering passage 24. The air passage thus 90 formed establishing communication between compressed air supply pipe 20 and the air nozzle 12 is controlled by an elongated valve member 25 which is mounted for longitudinal sliding in the handle piece 22, the 95 front end of said member 25 being adapted to traverse said passage as shown.

The opposite end of the member 25 projects downwardly into engagement with a sleeve or collar 26 which is slidably mounted 100 upon handle piece 22 so that, upon shifting of said sleeve, said valve member will be moved. The under side of handle piece 22 is longitudinally slotted as at 27 to afford

clearance for the downwardly projecting portion of said valve member. A helical compression spring 28 engaging against the outer end of member 26 serves to normally hold the valve 25 in closed position.

In using the device, the reservoir 8 having been supplied with the ink, paint or other liquid pigment desired and the tube 20 having been connected with a source of compressed air supply, to effect discharge from the device it is only necessary to rotatably adjust the valve 15 and to retract the sleeve 26. When this is done it will be seen that compressed air will be admitted to and discharged from the nozzle 12 which will result in the creation of a suction in the passage 2, the suction thus created causing liquid pigment to be automatically drawn up through the pipe 6 into the passage 2 and discharged with the compressed air through the nozzle 12. The formation of the air passage 16 is such as to be readily accessible for cleaning upon removal of nozzle 12 and the construction is such as to permit of economical manufacture. The arrangement of the air controlled valve 25 permits of ready and easy movement thereof, the sleeve 26 being located in close proximity with the grip 23.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In an air brush, the combination of a pigment and an air nozzle; a pigment supply reservoir in communication with said pigment nozzle; a valve for controlling communication between said pigment reservoir and said pigment nozzle; an exteriorly positioned handle on said valve; a passage communicating with said air nozzle and disposed at right angles thereto for the supply of compressed air thereto; a handle piece projecting from said air passage at substantially right angles thereto and substantially parallel with the axes of said nozzles; means for controlling said air passage, said means comprising an elongated longitudinally slidable valve member mounted in said handle piece and having one end adapted to traverse said passage; a sleeve slidably mounted on said handle piece in close proximity with said before mentioned valve handle, said sleeve engaging with the

opposite end of said valve member for manually retracting said valve member; and a spring engaging with said sleeve for normally holding said valve member in closing position, substantially as described.

2. In an air brush, the combination of a pigment and an air nozzle; a pigment supply reservoir in communication with said pigment nozzle; a rotatable valve for controlling communication between said pigment reservoir and said pigment nozzle; an exteriorly positioned head on said valve for rotating the same; a passage communicating with said air nozzle and disposed at right angles thereto for the supply of compressed air thereto; a handle piece projecting from said passage at substantially right angles thereto and substantially parallel with the axes of said nozzles; a grip provided on the outer end of said handle piece; means for controlling said air passage, said means comprising an elongated longitudinally slidable valve member mounted in said handle piece and having one end adapted to traverse said passage; a sleeve shiftably mounted on said handle piece in close proximity with the inner end of said grip and said before mentioned valve actuating head for retracting said valve member; and a spring engaging against said sleeve for normally holding said valve member in closing position, substantially as described.

3. In an air brush, the combination of a pigment and an air nozzle; a pigment supply reservoir in communication with said pigment nozzle; means for supplying compressed air to said air nozzle; means for controlling the flow of the liquid from said pigment nozzle; a handle piece; a valve for controlling the flow of compressed air to said air nozzle; and a conical sleeve on said handle for actuating said valve, substantially as described.

4. In an air-brush, the combination of a pigment nozzle and an air nozzle, a source of pigment supply and a source of air supply communicating with said nozzles respectively, a handle, reciprocating means adjacent said handle for controlling the air supply, and rotary means adjacent said handle for controlling the pigment supply, said reciprocating means and said rotary means being operable independently by different fingers of the hand grasping said handle, and the axis of rotation of said rotary means being substantially parallel to the path of reciprocation of said reciprocating means, substantially as described.

5. In an air-brush, the combination of concentric pigment and air nozzles, a source of pigment supply and a source of air supply communicating with said nozzles respectively, a handle substantially parallel

with the axis of said nozzles and in a plane below the same, rotary means for controlling the pigment supply and including a knurled member adjacent the forward end 5 of said handle and slightly above the same, and reciprocating means on the said handle adjacent said knurled member, for controlling the air supply, whereby the pigment supply and the air supply may be controlled

independently by fingers of the hand grasping said handle, substantially as described.

In testimony whereof I have signed my name to this specification in the presence of two subscribing witnesses.

AUGUST KOPINSKI.
